UNITED STATES PATENT OFFICE.

FREDERIC B. WOOD, OF PROVIDENCE, RHODE ISLAND, ASSIGNOR TO RHODE ISLAND FIBER SPOOL COMPANY, OF PROVIDENCE, RHODE ISLAND, A CORPORATION OF RHODE ISLAND.

SPOOL.

SPECIFICATION forming part of Letters Patent No. 782,942, dated February 21, 1905.

Application filed March 5, 1904. Serial No. 196,702.

To all whom it may concern:

Be it known that I, FREDERIC B. WOOD, a resident of the city of Providence, in the county of Providence and State of Rhode Island, have 5 invented certain new and useful Improvements in Spools or Reels; and I do hereby declare that the following is a full, clear, and exact description thereof, reference being had to the accompanying drawings, and to the figures of reference marked thereon, which form a part of this specification.

This invention relates to spools on which may be wound wire or yarn principally for use in the wire trade or textile mills.

15 The object of my invention is to provide a spool very simple in construction that will be practically indestructible, extremely light in weight, and inexpensive to manufacture.

Spools when heavily laden with wire are liable 20 to accidental dropping as well as to careless handling. When wound with yarn and used in the mill, they receive extremely rough usage, and great strength is consequently required for withstanding injury. While strength is 25 an obvious necessity in such spools, it is of importance that they be as light as is consistent for the uses intended. In addition to the strength required to withstand the rough handling it is also found in practice that great 30 pressure is brought to bear against the heads, having a tendency to crowd or force them off of the ends of the barrel. To withstand this latter strain, I have devised means whereby a natural lock is formed on the ends of the body, 35 or barrel, so that the greater the pressure to force these heads off the tighter they are locked and bound in place.

Another essential feature of my invention 40 is the construction of the tubular barrel of corrugated metal instead of making it of plain stock. By this construction a number of important advantages are obtained, the principal of which being that the strength and rigidity of the barrel is greatly increased, thereby 45 allowing a much thinner stock to be used and the weight proportionally to be reduced. Then, again, by corrugating the working face

of this barrel and leaving the ends plain a natural shoulder is formed against which the inner face of the heads may rest. The rough 50 surface of the corrugations catch and retain the ends of the threads when yarn is wound thereon, and the scores or grooves in the barrel form a natural guide for the knife which is used to strip off the waste threads from the 55 spool when the yarn has been unwound therefrom.

With these and other advantages in view the invention consists of certain novel features 60 of construction, combination, and arrangement of parts, as will be more fully described, and particularly pointed out in the appended claims.

In the accompanying drawings, Figure 1 shows my spool in elevation. Fig. 2 is an enlarged sectional view showing one end of the spool and illustrating my improved manner of binding the heads in place. Fig. 3 shows a portion of the corrugated drum with the end left plain, forming a shoulder. Fig. 4 shows 65 this plain end as cut out, forming a plurality of dovetailed wedges. Fig. 5 is a sectional view of one end, showing these dovetailed ends turned up in the position they take when the head is locked in place. Fig. 6 is a sectional 70 end view on line 6-6 of Fig. 3, showing the corrugations in the tubular barrel. Fig. 7 shows the wedging-plug, which is forced into the end of the tubular barrel. Fig. 8 is an enlarged section of the head, showing the beveled 75 opening which receives the locking wedge-shaped ends of the tubular barrel.

Referring to the drawings, 11 are circular 80 disks which form the heads or ends of the spool. These disks may be constructed of any suitable material; but paper fiber is preferably used, as it is found to be much more satisfactory for withstanding the shocks and strains these heads are submitted to without splitting, bending, or breaking. Each disk 90 has a hole through its center, said hole being outwardly beveled at 8, as illustrated in Figs. 2 and 8. This beveled portion is for the purpose of receiving and retaining the dovetailed

ends of the tubular barrel. The body or barrel 2, onto the ends of which the heads are fixed, is preferably constructed of metal and made in a tubular form, and while a plain barrel may be used for this purpose I preferably employ the corrugated barrel for reasons above explained. When the metal which forms the barrel is crimped or corrugated, a plain portion 3 is left on each end thereof to be inserted into the heads. The raising of the surface of this metal by crimping or corrugating forms a natural shoulder 4 to the plain portion, against which the inner face of the heads may rest. The stock on the ends of the barrel may be left plain, or it may be slit to facilitate spreading the ends, or cut out, so as to form a plurality of dovetailed fingers, as illustrated at 5 in Figs. 4 and 5.

At 6 is the locking-plug, preferably made of wood or fiber. The barrel portion 7 of this plug is made to fit tightly into the end of the tubular barrel. The outer end or head of this plug is made somewhat larger and joins the body of the plug by a slightly - tapered portion 9.

The assembling of the parts of this spool or reel is extremely simple and can be done very rapidly and without the aid of skilled labor. All the tools necessary to do this work is an ordinary press, which may be worked by either foot or power. The operator takes a prepared tube or barrel, and slips a head on either end until it rests against the shoulder 4. A plug 6 is then inserted into each end of the tube and the whole submitted to the action of the press, which forces the tightly - fitting plugs into the tube, spreads the dovetailed fingers out into the beveled portion 8 of the hole in the head, and the final pressure sets these dovetailed fingers down into the fiber and into the beveled portion of the plug and the spool is completed.

It is obvious in my improved construction that by opening the ends of the tube out into the counterbored portion of the head and holding them there by the beveled portion of the plug any outward strain or pressure on the head simply has a tendency to force said fingers down deeper into the plug and automatically bind or lock the whole more tightly together. It will also be seen that the shape of the dovetailed fingers, which are countersunk into both the head and the plug, naturally have a tendency to hold and retain the plug and resist any outward movement of either, thus doing away with the necessity of gluing. Then, again, by setting the fingers into the head they act as keys for the same, effectually preventing the heads from turning. This spool is exceedingly simple and practical in construction.

Having thus described my invention, what I claim as new, and desire to secure by Letters Patent, is—

1. In a spool or reel, a corrugated barrel having plain or uncorrugated ends made inter-

gral therewith, a shoulder formed by the corrugations at the junction of the plain and the corrugated portions for the purpose of preventing the heads from being forced onto said corrugated portion, said heads, and means for securing them to said uncorrugated portion of the barrel.

2. In a spool or reel, a tubular corrugated body having plain or uncorrugated ends all made in one piece, a shoulder formed on the plain surface by raising the surface on the corrugated portion, heads fitted to said plain ends their inner faces resting against said shoulders and means for expanding the ends of said tubular body to prevent the heads from coming off.

3. In a spool or reel, a tubular corrugated body having plain or uncorrugated ends, all made in one piece, said plain ends being slit to allow for expansion, a shoulder formed on the plain surface by raising the surface on the corrugated portion, heads fitted to said plain ends their inner faces resting against said shoulders, said heads being provided with central counterbored holes, and a plug having a beveled portion arranged to be driven into the ends of said tubular body to expand the stock into the counterbored portion of said heads.

4. In a spool or reel, a corrugated tubular body having plain or uncorrugated ends, a shoulder formed by the corrugations at the junction of the plain and the corrugated portions, heads fitted on the plain portion of the barrel to rest against said shoulder, said heads being provided with counterbored holes, and a plug having a beveled portion arranged to be driven into the tubular body and expand the ends of the same into the counterbored portion of the heads.

5. In a spool or reel, a corrugated metal body or barrel having plain or uncorrugated ends, the corrugated portion of said barrel forming a shoulder at each end against which the heads of the spool may rest, a head being provided with central counterbored holes, said heads being fitted onto each end of said barrel, and a plug to be driven into said tube for expanding the ends of said barrel into said counterbored portion of said heads.

6. In a spool or reel, a body or barrel, corrugations on a portion of said body only, the ends of said body being left plain or uncorrugated, a shoulder formed by the corrugations at each end at the junction of said corrugated and uncorrugated portions, heads fitted on the plain portion of the barrel to rest against the shoulder formed thereon, said heads being provided with counterbored holes, and a plug to be driven into said barrel for expanding the ends of the same into the counterbored portion of the heads.

7. In a spool or reel, a body or barrel, corrugations on a portion of said body only, the ends of said body being left plain or uncorrugated, a shoulder formed by the corrugations

at each end at the junction of said corrugated and uncorrugated portions of the barrel, the uncorrugated ends of said barrel being cut to form a plurality of dovetailed wedges, heads fitted onto the ends of said barrel, each head being provided with a counterbored hole, a

5 plug to be driven into the tubular ends of said barrel, and a beveled portion on said plugs to engage and expand said dovetailed ends of the

barrel into said counterbored portion of said heads.

In testimony whereof I have hereunto set my hand this 3d day of March, A. D. 1904.
